UNITED STATES PATENT OFFICE.

MOSES J. DAVIS, OF PUEBLO, COLORADO.

DEVICE FOR POLISHING BUTTONS.

Application filed November 10, 1925. Serial No. 68,149.

This invention relates to a device for polishing metal buttons, one of the objects being to provide a simple and efficient device which can be applied to a garment and be used for polishing the buttons thereon without soiling or otherwise injuring the garment, without soiling the hands, and without danger of injury to the buttons being acted on.

10 It is essential that the brass buttons and buttons of other metals worn on uniforms of railway conductors, policemen, firemen, and others be maintained bright at all times. Heretofore it has been necessary to use various cleaning preparations for this purpose and it has been difficult to employ these preparations without soiling the hands or the garment.

It is an object of the present invention to 20 overcome the objections heretofore present during the cleaning operation.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 25 within the scope of what is claimed without departing from the spirit of the invention.

In the accompanying drawings the preferred form of the invention has been shown.

In said drawings,

25 Figure 1 is a longitudinal section through the device, the same being shown in use.

Figure 2 is a section on line 2—2 Figure 1.

Figure 3 is a perspective view of the two members of the housing pulled apart.

40 Referring to the figures by characters of reference 1 designates a housing member closed at one end, as shown at 2 and having its side walls 3 connected for a portion of their length by a bottom 4. The top of this member 1 is open and one end thereof is also open. The other member 5 includes side walls 6 connected by a bottom 7, an end wall 8, and a top 9. Angular arms 10 are extended from the open end of the section 5 and constitute continuations of portions of the top 9 and of the side walls 6, these arms forming a slot 11 between them. The arms are designed to engage and lap the upper edge portions of the walls 3 and when the members 1 and 5 are thrust toward each other the walls 3 will enter the member

5 between the walls 6 while the bottom 7 will slide under the walls 3 to a position close to the bottom 4 of the member 1.

A brush is mounted to reciprocate within the extensible casing formed by the slidably connected members 1 and 5, this brush including a head 12 from which are extended long wire bristles 13. A handle 14 is connected to the block 12 by a neck 15 mounted to slide within the slot 11, it being understood that the head 14 will properly support the brush within the casing.

In practice it has been found desirable to use bristles 13 not less than one inch in 70 length. Where shorter lengths are employed the wires tend to kink while in use.

In Figure 1 a piece of fabric has been indicated generally at F and a metal button attached thereto has been indicated at B. 75 When it is desired to polish the button the members 1 and 5 of the casing are moved apart so as to provide a sufficient space between the bottoms 4 and 7 to permit the insertion of the button into the casing. The 80 members of the casing are then pressed toward each other so that the bottoms 4 and 7 will come to position back of the button as shown in Figure 1. The brush is then reciprocated within the casing and the bristles 85 will pass back and forth over the button and quickly polish the same. The casing can then be extended to release the button after which it can be applied to another button quickly and the foregoing operation 90 repeated.

What is claimed is:

1. A polishing device of the class described including a casing comprising interfitting relatively movable members for the 95 reception of a button, and a polishing element mounted for reciprocation within the casing.

2. The combination with a casing including interfitting relatively movable members 100 for receiving a button therebetween and holding the button, there being a slot within one of the members, of a brush movably mounted within the casing, and means on the brush cooperating with the walls of the slot 105 for guiding the brush during the reciprocation thereof.

In testimony that I claim the foregoing as my own, I have hereto affixed my signature.

MOSES J. DAVIS.
